5 Sheets-Sheet 1

A technical line drawing of a mechanical apparatus, identified as Figure 1. The drawing shows a side view of a frame structure with various components labeled with numbers. At the top, a horizontal beam is labeled 5 and 12. A vertical support is labeled 11. A triangular hopper or conveyor section is labeled 10. A large wheel assembly is labeled 2, 20, and 30. A vertical pipe or cylinder is labeled 3. The drawing is annotated with several numbers: 5, 10, 11, 12, 15, 16, 17, 18, 19, 20, 22, 28, 29, 30, and 31. The entire drawing is signed 'Fig. 1.' in the top right corner.

A technical line drawing of a dump truck. The truck is shown from a three-quarter perspective, tilted forward. The body is a large rectangular container with a hinged rear door. A hydraulic cylinder assembly, labeled with numbers 11, 5, 10, 15, 19, 16, 18, 22, 20, and 30, is attached to the side of the body and the rear door. A large wheel is visible at the front left. The truck is mounted on a simple frame with a single rear wheel. The drawing is signed 'Fig. 2.' in the top right corner.

TRANSPORTING AND DUMPING EQUIPMENT

George R. Dempster, Harry W. Jones, and William A. Herpich, Knoxville, Tenn.; said Jones and said Herpich assignors to Dempster Brothers, Inc., Knoxville, Tenn., a corporation of Tennessee

Filed Oct. 8, 1956, Ser. No. 614,683

9 Claims. (Cl. 214—75)

This invention relates to improvements in transporting and dumping equipment, and more particularly to the type of equipment set forth in the prior patent of George R. Dempster, No. 2,281,183 granted April 28, 1942.

Equipment of the type set forth in the aforesaid patent, as manufactured and used heretofore, comprises a hoisting unit upon which a container is adapted to be supported during transportation to a desired point for dumping. The hoisting unit comprises a frame having a bucket rest or support mounted thereon upon which the container is adapted to be seated during transportation. A boom is mounted on the frame and has means for attachment to the container for lifting the container onto the bucket rest or support. A skid frame is also mounted on the frame of the hoisting device against which the container may rest and be drawn up in moving to its supported and dumping positions.

The bucket rest or support for the container is usually so located on the hoisting frame as to dispose the center of gravity of the container and its contents substantially over the rear axle of the vehicle or just slightly forward of the rear axle where the major part of the load can be taken by the latter during transportation of the vehicle. Containers of standard or conventional sizes can be accommodated on the bucket rests of hoisting units of standard sizes. However, for relatively lightweight materials extremely large or elongated containers are often desirable. If such containers, however, were used on conventional sized hoisting units, they would overhang the back end of the hoisting unit resulting in serious danger of falling off the vehicle during transportation or becoming overbalanced either during picking up or dumping. No adequate provision has been made heretofore for handling such abnormally large containers as is often desirable.

One object of this invention is to overcome the objections noted especially for abnormally large or long containers that may be accommodated on the bucket rest and yet will not seriously overhang the back end of the vehicle during transportation.

Another object of the invention is to improve the construction of the bucket rest to accommodate containers of different sizes, both the conventional sized containers and those that are abnormally large, and yet to provide for effective support thereof on the vehicle.

Still another object of the invention is to provide for the shifting of the bucket rest to different positions with respect to the vehicle and thereby to provide for the handling of different sized containers by the same hoisting unit with adequate provision for effective support of the containers on the vehicle at all times.

These objects may be accomplished according to one embodiment of the invention by providing bucket rests on the hoisting unit capable of shifting movement to retracted and extended positions, respectively, so as to accommodate a container of the desired size in either position of the bucket rests. The extended bucket rests 70 may be formed as parts of the hoisting unit or as attach-

2

ments for the conventional bucket rests, slideable thereover and capable of shifting movement to retracted and extended positions. Suitable means may be used for effecting the shifting of the bucket rests to their respective positions or these may be shifted by hand, according to the different embodiments set forth in the drawings.

In the accompanying drawings:

Fig. 1 is a side elevation of a hoisting unit and container supported on the bucket rests in retracted position.

10 Fig. 2 is a similar view showing an enlarged container mounted on the extended bucket rests.

Fig. 3 is a perspective view of the bucket rests in extended position and supporting the container.

15 Fig. 4 is a top plan view of one of the bucket rests with one form of operating means therefor;

Fig. 5 is a side elevation thereof;

Fig. 6 is a perspective view showing the bucket rests in retracted positions;

Fig. 7 is a cross-section through the mounting of a 20 bucket rest, substantially on line 7—7 in Fig. 5;

Fig. 8 is a side elevation showing a modification of the operating means for the bucket rests; and

25 Fig. 9 is a side elevation, showing a further modification of the bucket rest extension and operating means therefor.

The invention is illustrated as applied to a hoisting unit substantially of the character set forth in the aforesaid patent of George R. Dempster, No. 2,281,183, granted April 28, 1942. This hoisting unit is mounted on a truck 30 chassis, the frame of which is indicated generally by the numeral 1, supported on wheels 2. The cab is shown at 3.

35 Mounted on the chassis frame 1 is a subframe 4 extending lengthwise of the vehicle in this embodiment of the invention. A boom is indicated at 5 comprising a pair of spaced arms on opposite sides of the chassis, pivotally supported at 6 on the subframe 4. The boom 5 is adapted to be raised and lowered with respect to the subframe 4 by hydraulic power devices generally indicated at 7.

40 At the rear end of the subframe 4 and mounted thereon are bucket rests generally indicated at 8. These bucket rests 8 are located on opposite sides of the chassis and subframe 4 and are formed of structural members rigidly secured to the subframe. Each of the boom rests usually has an inclined upper edge surface shown at 9 upon which a container is adapted to be seated during transportation of the unit.

45 The container is shown in Fig. 1 at C, being a conventional form of drop bottom container, of normal size, which does not unduly overhang the rear end of the hoisting unit. Each container usually has lifting pins 10 on opposite ends thereof, which may be connected with the drop bottom of the container in the illustrated form thereof. The arms of the boom 5 are connected with the lifting pins 10 through flexible cable devices generally indicated at 11, and which usually comprise lifting chains.

50 A movable carriage is shown at 12 operatively mounted on the hoisting unit, as by means of rollers 13 mounted in tracks 14 shown in Figs. 3 and 6 of the drawings.

55 The hoisting unit heretofore described is shown more in detail and its operation set forth more fully in the aforesaid patent of George R. Dempster, No. 2,281,183, granted April 28, 1942.

60 As will be apparent from Fig. 6, the bucket rests 8 are spaced apart transversely of the hoisting unit being mounted on the laterally spaced members of the subframe 4 and secured rigidly thereto. In this embodiment of the invention we have provided extension members or shoes 15 fitted over each of the bucket rests 8 and supported thereon. Each of the extensions 15 is U-shaped in cross-section, embracing the upper edge of

the bucket rest 8 and being connected therewith by a transverse bolt 16 as shown in Figs. 4, 5 and 7. The bolt 16 extends transversely through opposite sides of the U-shaped extension 15 and through the structural member forming the bucket rest 8. Slots are provided at 17 in the opposite sides of the extension member 15 through which the bolt 16 extends, whereby the extension member may be moved back and forth with respect to the bucket rest 8 through the length of the slots 17 as will be apparent by comparing Figs. 3 and 5 showing one position thereof with Fig. 6 which illustrates the opposite position thereof.

The extensions 15 may be moved with respect to the bucket rests 8 either manually or by power devices such as hydraulic, vacuum or air cylinders, linkage or electric solenoids.

As shown in Figs. 3 to 6, a bell crank lever 18 is pivotally connected at 19 with each of the extension members 15, at one end of the bell crank lever 18, while the opposite end of said bell crank lever is pivotally supported at 20 on the subframe 4. A rod 21 extends lengthwise of the subframe 4 and is pivotally connected at 22 to the bell crank lever 18 intermediate its ends.

Any suitable means may be used as desired for actuating the rods 21 to move the extension members 15 to extended and retracted positions, respectively. Such actuating means may be operated manually or by power, examples of which are shown in Figs. 4, 5 and 8.

As illustrated in Figs. 4 and 5, lever arms 23 are connected with respective push and pull rods 21 by being pivoted to the free ends thereof at 24. Each lever arm 23 is pivotally supported at 25 on a mounting bracket 26 secured on the subframe member 4. Also fixed to the lever arms 23 at the pivots 25 are lever arm extensions 27 which are connected together by a handle 28 extending transversely across the hoisting unit. The extension lever arms 27 being fixed to the arms 23 will cause movement thereof and of the push and pull rods 21 upon manipulation of the handle 28 to the different positions illustrated by full lines and dotted lines in Fig. 5, thereby to move the extension members 15 between the extended and retracted positions thereof as will be apparent from Fig. 5.

It is also possible, as noted above, to use suitable power means for operating the push and pull rods 21 by connecting power devices thereto as illustrated in Fig. 8 and designated generally by the numeral 29. Each of the power devices 29 may be connected between the respective push and pull rods 21 and the mounting brackets 26 substantially in the same relation indicated in Figs. 5 and 8. Any suitable power devices may be used for this purpose, such as hydraulic, vacuum or air cylinders, electric solenoids or the like, and which are generically illustrated in Fig. 8.

The operation of the boom rest extensions will be apparent from the foregoing description in connection with the illustrations in the drawings. These extensions 15 are shown in different positions according to the size of container that is to be handled by the hoisting unit. The operation of the hoisting means is described more in detail in the prior patent of George R. Dempster, No. 2,281,183, and need not be repeated herein since these hoisting units are well known in the art.

Where containers of the normal conventional sizes, such as indicated at C in Figs. 1 and 6, are to be handled on the hoisting unit, the boom rest extensions 15 are moved to their retracted positions and the boom rests with their inclined upper surfaces 9 will be sufficiently extended to support the container securely on the vehicle during transportation. This also locates the center of gravity of the load substantially over the rear axle or slightly forward thereof.

For an abnormally large container that would not be accommodated on the boom rest surfaces 9 without material overhang, as indicated at C' in Figs. 2 and 3,

some extension of the boom rest surfaces 9 is needed for secure support of the container. In that event, the extensions 15 are operated to be moved to the extended positions shown in Figs. 3 to 5 and thereby extend the surfaces 9 sufficiently to form secure supports underneath the elongated container C'. The length of these extensions 15 will depend upon the size of the container to be handled thereon but should be sufficient so that the major part of the load will be carried on the boom rest surfaces with no appreciable danger of tipping of the container off these surfaces during transportation. The container rests against the movable carriage 12 at the forward end of the boom rest surfaces 9 in an inclined position as will be apparent from the drawings. Some overhang beyond the ends of the extensions 15 is not objectionable so long as the major part of the load is carried forward of the rear ends of these extensions.

The boom rest extensions 15 in their retracted positions are located forward of the rear apron 30 up which the container is adapted to be drawn by the hoisting unit and particularly by the boom 5 and lifting chains 11. When thus lifting the container up for transportation on the hoisting unit, the carriage 12 is in its rearmost position as indicated in Fig. 6. Thus, the container can be drawn up along the skid surface on the carriage and this movement will not be interfered with by the boom rest extensions 15 which then would be in their retracted positions, as shown therein. After the container is thus raised to a position above the boom rests, the extensions 15 can be projected to their extended positions shown in Figs. 3 and 5 underneath the container either by hand or by the power means described above, and thereafter upon movement of the carriage 12 forward to the front ends of the boom rest surfaces, as illustrated in Fig. 5, the container can be set down upon the boom rest surfaces as in Fig. 3. In this position it can be carried to the point of dumping where its contents can be discharged and thereafter it can be moved to the point of use for refilling.

In the modification illustrated in Fig. 9, the bucket rest and extension, and parts which correspond with those described above, are identified by the same numerals applied thereto. In this form, the extensions 15, instead of being operated by bell cranks 18, or other means at the front ends of the extensions, have the push bars connected with the rear end portions thereof.

Each of the extensions 15 has a push bar 30 pivotally connected with the lateral skirt on the extension, at the point indicated at 31. The rear end of the push bar 30 is pivotally connected at 32 to the depending end of a lever arm 33. The lever 33 is permanently fixed at its upper end portion to an upstanding lever arm 34, and these lever arms 33-34 are pivotally mounted at 35 on a bracket 36 on the subframe 4.

At the upper end of the lever arm 34 is a contact bar 37, one end of which is fixed to the lever arm 34 by a locking clutch engagement therewith, indicated generally at 38. The opposite end of the contact bar 37 has a laterally extending rounded nose portion, generally indicated at 39, in position to engage the carriage 12 of the hoisting means beneath a stop shoulder 40 on the carriage 12. This shoulder may be formed by welding a clip to the forward face of the carriage channel, or by other suitable means as desired.

Normally, the extensions 15 are in their retracted positions relative to the bucket rests 8, being held in such positions by coiled springs 41 that are anchored in suitable positions on the subframe 4 and connected with the depending arms 35. These normal positions are illustrated by dotted lines in Fig. 9, and it will be apparent therefrom that the springs 41 also project the contact bars 37 to the forward dotted line positions illustrated in the drawing.

When an extra wide container has been picked up by the hoisting means and is held on the carriage 12, it is

moved inward with the carriage, as described above. When the channel on the forward face of the carriage reaches the dotted line position illustrated in Fig. 9, the forward face thereof engages the nose 39 on each contact bar 37. This contact bar 37 is fixed in relation to the lever arm 34 so that it cannot swing with respect thereto, and the continued forward movement of the carriage 12 pushes on the contact bar 37, thereby swinging the lever arm 34 about the pivot 35, thus moving the lever arm 33 against the tension of the spring 41 to the full line position shown in Fig. 9. The lever 33 causes forward linear movement of the push bar 30 to project the extension 15 to the full line position shown in Fig. 9, beneath the enlarged container C' (Fig. 2). The container then may be set down on the bucket rest 8 and extension 15, and will be supported effectively thereon during transportation.

As soon as the container is picked up by the hoisting means off the bucket rest 8 and extension 15, and the carriage 12 moved rearward of the subframe 4 beyond the point indicated in dotted lines in Fig. 9, the springs 41 acting on the lever arms 33 will swing the latter to the dotted line positions shown, thereby pulling the bars 30 and extensions 15 to their retracted dotted line positions.

When the extensions 15 are not needed, they can be put out of operation merely by swinging the contact bars 37 to the intermediate dotted line positions shown in Fig. 9. This may be done by loosening the clutch connections 38 and swinging these contact bars back. The lever arms 34 and contact bars 37 are displaced laterally of the channels of the carriage 12 so as not to engage the latter when the nose portions 39 are moved to such retracted positions. These nose portions normally overlap the rear faces of the channels, forming lateral projections on the contact bars.

We have provided a very simple and effective extension of the boom rests on hoisting units which allows us to carry extra long containers, the center of gravity of which would not allow them to be carried on conventional bucket rests. The extensions are simple and inexpensive and may be added to conventional equipment without appreciable modification and at little cost.

While the invention has been illustrated and described in certain embodiments, it is recognized that other variations and changes can be made therein without departing from the invention, as set forth in the claims.

We claim:

1. In transporting equipment adapted to be mounted on a vehicle chassis and including a pair of bucket rests having supporting surfaces adapted to be mounted on the rear end of the chassis to receive a container thereon, and means for lifting a container to a seated position on the supporting surfaces of the bucket rests, the combination therewith, of extension members slidably mounted on the rear ends of the bucket rests to support an oversized container, each of the extension members being substantially U-shaped in cross-section and embracing the supporting surface of a bucket rest, and means connected to said chassis and extension members for mounting said extension members to extended and retracted positions substantially in alignment with the supporting surfaces of the respective bucket rests to cooperate therewith in supporting the container.

2. In transporting equipment adapted to be mounted on a vehicle chassis at the rear end thereof and including a pair of bucket rests having supporting surfaces adapted to receive a container thereon, and means for lifting a container to a seated position on the supporting surfaces of the bucket rests, the combination therewith, of extension members, each of the extension members being substantially U-shaped in cross-section and embracing the supporting surfaces of the bucket rests, and means mounting the extension members on the bucket rests for sliding movement to extended and retracted positions with re-

spect thereto substantially in alignment with the supporting surfaces of the respective bucket rests to cooperate therewith in supporting the container, bell crank levers connected with the extensions, and push and pull rods connected with the bell crank levers for moving said extensions with respect to the bucket rests.

3. In transporting equipment, the combination with a vehicle chassis having a depending apron at the rear end thereof, of a hoisting unit mounted on the vehicle chassis comprising a pair of bucket rests extending forwardly of the apron with supporting surfaces inclined toward the rear of the vehicle chassis, a container mounted on the bucket rests and extending rearwardly of the apron therefrom, hoisting means for raising and lowering the container with respect to the bucket rests and for moving the container to a seated position on the supporting surfaces thereon, and extension members slidably mounted on the rear ends of the bucket rests to support an oversized container and arranged substantially in alignment with the supporting surfaces of the bucket rests and extending rearwardly of the apron underlying and supporting the container, and means connected to said chassis and extension members for moving said extension members to extended and retracted positions with respect to said bucket rest.

4. In transporting equipment adapted to be mounted on a vehicle chassis and including a pair of inclined bucket rests having supporting surfaces adapted to be mounted on the rear end of the chassis to receive a container thereon, and means for lifting a container to a seated position on the bucket rests, the combination therewith, of extension members slidably mounted on the rear ends of the bucket rests to support an oversized container and arranged substantially in alignment with the supporting surfaces of the bucket rests, and means connected to said chassis and extension members for moving said extension members to extended and retracted positions with respect to said bucket rests in alignment with the supporting surfaces to support the container thereon.

5. In transporting equipment the combination with a vehicle chassis having a depending apron at the rear end thereof, a pair of bucket rests mounted on the vehicle chassis forwardly of said depending apron and having supporting surfaces thereon, an oversized container seated upon the supporting surfaces, means mounted on the vehicle chassis for raising and lowering the container with respect thereto, U-shaped extension members slidably mounted on the supporting surfaces of the bucket rests and extending rearwardly beyond and upright plane through the depending apron in underlying supporting relation with the container, and means connected to said chassis and extension members for moving the extension members to extended and retracted positions with respect to the bucket rests.

6. In transporting equipment adapted to be mounted on a vehicle chassis at the rear end thereof and including a bucket rest adapted to receive a container thereon, and means for lifting a container to a seated position on the bucket rest, the combination therewith, of an elongated extension member, means mounting one end of the extension member on the bucket rest for lengthwise sliding movement relative thereto, and means for rocking the opposite end portion of said extension member vertically during the sliding adjustment thereof.

7. In transporting equipment adapted to be mounted on a vehicle chassis and including a bucket rest adapted to be mounted on the rear end of the chassis to receive a container thereon, and means for lifting a container to a seated position on the bucket rest, the combination therewith of an extension member slidably mounted on the rear end of the bucket rest to support an oversized container, and means connected to said chassis and extension member for moving said extension member to extended and restricted positions with respect to said bucket rest.

8. In transporting equipment adapted to be mounted on a vehicle chassis and including a bucket rest adapted to be mounted on the rear end of the chassis to receive a container thereon, means for lifting a container to a seated position on the bucket rest, the combination therewith, of an extension member slidably mounted on the rear end of the bucket rest to support an oversized container, said extension member being movable to extended and retracted positions with respect to said bucket rest, and means movable by the forward movement of the container when lifted above the bucket rest by said lifting means to automatically move the extension member to the extended position.

9. In transporting equipment adapted to be mounted on a vehicle chassis and including a bucket rest adapted to be mounted on the rear end of the chassis to receive a container thereon, and means for lifting a container to a seated position on the bucket rest, the combination therewith, of an extension member slidably mounted on the rear end of the bucket rest to support an oversized container, and lever means connected to said chassis and

extension member for moving said extension member to extended and retracted positions with respect to said bucket rest.
